Primary Examiner — Philip S Hyder*Assistant Examiner* — Darlington Ly(74) *Attorney, Agent, or Firm* — Muncey, Geissler, Olds & Lowe, PLLC(57) **CLAIM**

I claim the ornamental design for a hammerhead of impactor, as shown and described.

DESCRIPTION

FIG. 1 is a perspective view of a hammerhead of impactor showing my new design;

FIG. 2 is a front elevation view thereof, the rear being a mirror image;

FIG. 3 is a left side elevation view thereof, the right side being a mirror image;

FIG. 4 is a top plan view thereof; and,

FIG. 5 is a bottom plan view.
